UNITED STATES PATENT OFFICE

ROBERT J. BARTHOLOMEW, OF GERMANTOWN, PENNSYLVANIA, ASSIGNOR TO FLETCHER WORKS, INCORPORATED, OF PHILADELPHIA, PENNSYLVANIA, A CORPORATION OF PENNSYLVANIA

WHORL LATCH

Application filed February 5, 1931. Serial No. 513,627.

This invention relates to an improvement in whorl latches for locking the whorl spindles for silk throwing machines for example, the construction being such that the whorl and the spindle blade may be easily removed and replaced without loss of time, my construction being sufficiently rigid also to withstand the heavy pull and jerk to which the whorl and spindle blade are subjected by the operator when removing bobbins and the latch being held against vibration in the operation of the machine.

In the drawings:

Fig. 1 is an elevational view of a structure to which my invention has been applied and in which it has been shown in part sectional elevation; and

Fig. 2 is an elevational view at right angles to the showing of Fig. 1.

Referring to the drawings in detail, 1 designates the whorl to be latched provided with a flange 2 at its lower end which is to engage the latch.

The base 3 of the spindle structure is provided with a shoulder 4 and on this base is a 25 pressed steel latch support or bracket 5 which is forced on the base 3 until it abuts the shoulder 4.

This bracket has an upwardly extending portion 6, and straddling this portion 6 of the bracket is a latch 7, the latch being bifurcated for this purpose as shown at 8. The latch is pivoted on a pin 9.

The bracket 5 is also bifurcated as shown at 10 to permit of a spring 11 being applied to the pin 9. One end 12 of this spring engages the face of the bracket 5 while the other end 13 overlies the outer face of the latch 7.

The ends of the pivot pin 9 are spun over as shown at 14 sufficiently to lock the pin securely in place but not sufficiently to bind the latch.

It will be appreciated that the spring 11 will press the latch 7 firmly against the latch support thereby preventing the latch from rattling when the device is in operation. It will be appreciated also that the blade and whorl may be set in the spindle bolster without any extra operation on the part of the operator.

To remove the whorl and blade a slight lift of the latch 7 upwardly is sufficient to clear the flange 2 of the whorl, the engagement of the latch with this flange normally holding the whorl in place.

What I claim is:

1. In whorl latching mechanism the combination of a bracket having a bifurcated free end, a latch bifurcated at one end and straddling the bifurcated end of the bracket, a pivot pin passing through the bifurcated ends of the latch and bracket, a coil spring upon said pin, said spring being under tension and having one end engaging the inside of the bracket and its other end engaging the outer face of the latch, to hold the latch under tension on said pin.

2. In mechanism of the class described the combination of a base, a whorl supported thereon, a flange on the whorl, a shoulder on said base, a bracket frictionally secured to said base and engaging said shoulder, a portion of said bracket extending vertically substantially parallel to the whorl, a latch bifurcated at one end and straddling the upper end of said bracket, a pivot pin passing through the bracket and the bifurcated end of the latch, a spring upon said pin, said spring being under tension and having one end engaging the bracket and its other end engaging the latch to hold the latch under tension on said pin to reduce vibration of the latch when the whorl is rotating.

This specification signed this 2nd day of February, 1931.

ROBERT J. BARTHOLOMEW.
